(57) **CLAIM**

The ornamental design for a shoe crease remover, as shown and described.

DESCRIPTION

FIG. 1 is a top perspective view of a shoe crease remover, showing a first embodiment of my new design;

FIG. 2 is a bottom perspective view of FIG. 1;

FIG. 3 is a front elevational view of FIG. 1;

FIG. 4 is a rear elevational view of FIG. 1;

FIG. 5 is a left-side elevational view of FIG. 1;

FIG. 6 is a right-side elevational view of FIG. 1;

FIG. 7 is a top plan view of FIG. 1;

FIG. 8 is a bottom plan view of FIG. 1;

FIG. 9 is a top perspective view of a second embodiment thereof;

FIG. 10 is a bottom perspective view of FIG. 9;

FIG. 11 is a front elevational view of FIG. 9;

FIG. 12 is a rear elevational view of FIG. 9;

FIG. 13 is a left-side elevational view of FIG. 9;

FIG. 14 is a right-side elevational view of FIG. 9;

FIG. 15 is a top plan view of FIG. 9; and,

FIG. 16 is a bottom plan view of FIG. 9.

The broken lines in the figures depict portions of the shoe crease remover that form no part of the claimed design.

1 Claim, 16 Drawing Sheets
